UNITED STATES PATENT OFFICE.

HANS STEIDLE, OF MUNICH, GERMANY, ASSIGNOR TO SIEMENS & HALSKE, A. G., OF SIEMENSSTADT, NEAR BERLIN, GERMANY, A CORPORATION OF GERMANY.

TELEPHONE SYSTEM.

1,332,275.

Specification of Letters Patent.

Patented Mar. 2, 1920.

Application filed October 5, 1914, Serial No. 865,152. Renewed October 29, 1919. Serial No. 334,377.

To all whom it may concern:

Be it known that I, HANS STEIDLE, a German citizen, and resident of Munich, Bavaria, Germany, have invented certain new and useful Improvements in Telephone Systems, of which the following is a specification.

My invention relates to a telephone system with automatic or semi-automatic operation and branch-exchanges and has for its object primarily to provide an especial kind of line-selecting for such branch-exchanges.

In telephone systems as ordinarily constructed or proposed for automatic or semi-automatic service the so-called connectors have mostly been constructed for 100 or more subscriber connections, so that hundreds-groups will be obtained as smallest groups when subdividing the outside plant. The other systems which had been proposed relate entirely to an unlimited service, that is to say, to arrangements whereby the subscriber when calling will find at any time a free connecting line. It is known that the larger the groups are the smaller may be the percentage of incoming trunks.

Also systems of this kind have been constructed for a limited service which are ordinarily called branch-exchange systems; in this case for instance five subscribers are connected to a single trunk-line or ten subscriber lines are connected to two trunk lines. In the ordinary practice groups comprising each ten subscriber lines and two trunk-lines are most frequently used.

Such branch-exchanges are located in apartment houses or the like, where the traffic is small. The service rendered in such branch exchanges shall be restricted to some extent, that is to say, the service is to be sold at a lower rate than the unrestricted service. In the ordinary unrestricted service the subscriber will always get a free trunk line to any group of the system whenever he calls, whereas in the restricted service he will not be entitled to a free trunk line at every moment, he calls.

In the well known automatic telephone systems for unrestricted service it is common practice to combine the subscribers' lines into groups of 100 to 500 lines and to run about 10 to 40 trunk lines to these groups. These trunk lines start at so-called second or third selectors which are arranged to be set first by number impulses on the

contacts of the desired group and then to hunt for a free trunk line.

One object of my invention is to simplify the mechanism to be provided for the branch exchanges with restricted service.

60

Another object of my invention is to combine this simplified system with the well known system for unrestricted service.

In the drawings I have shown the well known Strowger type of switches as applied to the unrestricted system; it being, however, understood that the system is not limited to such type of switches.

Figure 1 diagrammatically shows the combination of the two types of exchanges referred to in a so-called four digit system. Figs. 2 and 2^a show a diagram in detail for establishing a talking connection between a subscriber of a main exchange with a subscriber of a branch exchange.

70

Referring to Fig. 1, N₁, N₂ designate subscribers' stations which pay for unrestricted service. The method for establishing a connection between the stations N₁, N₂ is well known, the first selector GW_I being set by the thousand digit, the second selector GW_{II} by the hundred digit, and the connector LW by the ten and unit digits.

75

N₃ designates a subscriber of a branch exchange.

80

Assume the station N₃ be numbered 525 and connected to the branch exchange GS numbered from 520 to 529. Nine other branch exchanges numbered 500 to 509, 510 and 519, and so on, may be provided in neighboring houses. Two trunk lines connect each branch exchange with the main exchange.

85

If now the subscriber N₁ wishes to call the subscriber N₃ (having the number 525) the setting of the first and second selectors GW_I, GW_{II} is accomplished in the well known manner. Each trunk line issuing from the fifth row of bank contacts of the second selector GW_{II} leads to a special selector S of which only one is shown in Fig. 1. The selector S has as many sets of wipers (b₁, b₂) as there are trunk lines running to each branch exchange. In the example shown two sets of wipers are provided. The subscriber N₁ will set the selector S by number impulses on the second row of contacts. If the trunk line l₁ leading to a switch L₁ of the branch exchange GS is engaged by another selector S the second set of wipers 100

105

110

(b_2) will come into operation. The subscriber N_1 will now be connected by the trunk line l_2 to the switch L_2 of the branch exchange GS. By a last set of number impulses the switch L_2 will be set on the desired number.

By this system the lines of the hundred subscribers (No. 500 to 599) may be made very short, and only 20 trunk lines are to be run to the main exchange, instead of carrying all hundred subscribers' lines to said main exchange.

In Fig. 2 I have shown in detail a diagram for establishing a connection between a subscriber's station N_1 of a main exchange and a subscriber's station N_3 of a branch-exchange. In this case I have shown a system controlled by number impulses in which during the rotation of the dial to its normal position the b -line constantly connected to ground whereas the a -line is alternately connected to ground and disconnected therefrom.

The setting of the first and second selectors GW_1 and GW_{II} is accomplished in the well known manner, it being understood that the line relay B is kept energized as long as the calling subscriber N_1 keeps his receiver off the hook. Therefore, the contact b_2' is also kept closed and the following circuit established: ground, contact b_2' , relay P_1 , wiper 12, relay C_1 , battery, ground. This circuit keeps said relay C_1 also energized. The relay C_1 closes the contact c_1 . If the selector GW_{II} has found a free selector S the testing relay P_2 in the second group-selector GW_{II} will respond, a circuit being established over ground contact c_1 of relay C_1 , relay P_2 , wiper 15, contact s_1 , relay C_2 , arm o_7 , battery and ground. The relays P_2 and C_2 will be excited and P_2 will close a contact p_2 , whereby the line will be guarded as known. The relay C_2 closes the contact c_2 in order to become independent from the contact o_7 . This latter contact o_7 is a seventh contact arm of the selector S , while the contact arms o_1, o_2, o_3 correspond to the set of brushes b_1 , the contact arms o_4, o_5, o_6 to the set of brushes b_2 , as shown in the arrangement according to Fig. 1.

If now the subscriber at the station N_1 again operates the dial, the relay X will be excited, the battery will be connected over the contact w_5 to the b -strand and relay B_1 of the selector S will be excited, a circuit being formed over ground, B_1 , contact s_6 , wipers 14, 11, b -strand, contact x_5 and battery, to ground. The excitation of this relay B_1 will be maintained until the dial returns to normal. During the return motion the flow of current will intermittently be interrupted over the calling a -strand and the armature of the relay A will fall off every time and close its contact a_5 . At each closing of the contact a_5 a current impulse

will be established over ground, a_5, x_3, a -strand, 10, 13, s_4 , relay A_1 , and battery, to ground. The impulse relay A_1 now closes a circuit for the rotary magnet D of the selector S over ground, rotary magnet D , k_3, a_3 , battery, ground. For each excitation of A_1 the seven contact arms o_1-o_7 will be moved one step.

The selector S being set upon the desired branch exchange two lines l_1 and l_2 may be available and now it must be tested which of these lines is free.

The relay C_2 having also closed the contact c_3 a circuit is established over ground, resistance, relay U , contacts k_2, c_3 , and battery, to ground. The relay U becomes energized and closes the contact u_1 so that it will remain excited, even if the contact k_2 will later be opened.

When operating the dial the relay B_1 has been excited as above described, and a circuit closed, ground, relay V , contact b_3 , parallel over k_2 and u_1, c_3 , battery, ground. The relay V becomes excited and closes its contacts v_4 and v_5 , thereby preparing circuits for the test relays T and R . If after sending the impulses the relay B_1 becomes deenergized, the relay V being slow-acting will still remain excited for some time; and keep closed the following circuit: ground, c_6, k_5, b_5, v_4 , and test relay T , brush o_3 , relay C_3 , battery, ground and ground, c_5, k_5, b_5, v_5 , relay R , brush o_6 and a further relay which corresponds to the relay C_3 (not shown).

If both lines l_1 and l_2 are free both relays T and R will respond, relay T will open the contact t_5 and close contact t_4 , so that the relay T will become independent from the contact v_4 . The relay R closes the contact r_4 . If the armature of the slow-acting relay V falls off and again opens the contacts v_4 and v_5 the relay T will remain excited over contact t_4 , the relay R , however, will become deenergized since circuit is interrupted at contact t_5 . If therefore both lines l_1 and l_2 are free they will both be engaged for a moment, the test device of the first line however will switch off the test relay of the second line. If line l_1 had been occupied and l_2 free, the relay R would have become excited and bound itself over the contacts r_4 and t_5 . If neither line l_1 or l_2 is free a busy signal will be given to the calling party, for if relay P_3 does not respond its contact p_3 will remain closed. The relay K , however, will become excited at any rate, as will be more fully described below. A circuit will therefore be established for the buzzer BS which indicates the occupied condition over BS , k_6, p_3 and induction coil J .

The series connection t_5 and r_4 replaces hunting devices for selecting a free line l_1, l_2 .

Assume the test relay T to respond. It will close a circuit: ground, P_3 , t_1 , q_4 , a_1 , battery, ground. The relay P_3 will take the function of the test relays T and R which must take place under all circumstances no matter whether T or R is responding.

When the armature of the slow-acting relay V falls off it closes a circuit: ground, battery, o_7 , relay K, v_1 and ground. The relay K is energized and closes its contact k_1 , thereby becoming independent from contact v_1 .

The relay K prevents the rotary magnet D of the selector S from responding to the next series of numeral impulses, by opening the contact k_3 . By opening the contact k_5 the relay K also prevents an additional testing by the relays T and R.

If now the subscriber at the station N_1 sends the last series of impulses the relay B_1 will again be excited. The circuit changes in the selector S are as follows:— When the back contact a_1 will be opened again a relay Q which had been short-circuited over the contacts a_1 and q_4 will be excited over ground, P_3 , t_1 , Q and battery. The relay Q opens the short-circuit at q_4 .

During the last series of number impulses there are excited the relays A₁, B₁, K, U, V, P_3 , Q and T. The purpose of the excitation of the relay V at this time is to open at contacts v_2 and v_3 , the feeding bridge formed by the relay S'. The excitation of the relay U in this moment has the purpose to keep open the contact u_2 in the circuit of the ringing relay L. When now at the calling station the α -strand is interrupted the relay A₁ in the selector S will be excited in the well known manner and close a circuit over battery, protective resistance W_2 , contacts a_2 , b_4 , l_3 , t_2 , brush o_1 , α -branch of the line l_1 , p_8 , impulse relay A₂, ground, thereby energizing the relay A₂. This will first excite a retarding relay F' over the circuit ground, a_{21} , F', battery, ground, which closes a contact f_1 . When the impulse relay A₁ in the selector S releases its armature and the relay A₂ becomes deenergized, the switching magnet H of the selector L₁ will be excited by a circuit over ground, f_1 , a_{41} , H and battery. The brushes o_8 , o_9 , o_{10} make one step. Simultaneously with the magnet H a slow-acting relay G which is connected in parallel to H is excited. After completion of the last series of impulses the relay F' will become deenergized and close its contact f_2 . By opening the contact f_1 the last current impulse for the rotary magnet H will be completed. Since now the relay G being more sluggish will fall off some time after the opening of the contact f_1 a test circuit for the relay P₄ will be temporarily closed over ground, c_6 , g , f_2 , P_4 , o_{10} , e , resistance W_3 and battery.

If the called party N_3 is free the relay P₄

will be excited and close a contact p_6 rendering the circuit of the test relay independent from the contacts f_2 and g , and guarding the engaged line.

The relay P₄ also closes a contact p_{10} , thus establishing a circuit over resistance W_4 . In the line leading to the station N_3 a relay E is inserted which will be excited in case of outgoing as well as incoming calls. This relay will thereby open the contact e , so that a connector when testing will not find battery over the resistance W_3 . It may be incidentally noted that the lines l for incoming and m for outgoing calls may be coupled to each other or may be identical lines.

If, the party N_3 be free, the relay P₄ will close the contact p_6 and p_7 and switch off the impulse relay A₂ at p_8 . Therefore no bridge remains over the talking leads in the branch exchange.

The relay V in the selector S, as above mentioned, had been excited during the sending of the last impulses and the feeding bridge S' had been switched off. If after completion of the last series of impulses the relay B₁ again falls off, first the contact b'_3 will be closed, thereby short-circuiting the relay U over b'_3 and q_2 . The relays U and V after some time will be deenergized. Relay U opens the contact u_1 and closes the contact u_2 . Contact u_2 closes a circuit from ground, relay L, u_2 , s_7 , c_4 , interrupter un , battery to ground. The relay L will periodically connect the line of the called station N_3 to a ringing current source over the contacts l_4 and l_6 . If the party N_3 answers, the feeding relay S' will be excited over battery, S', v_2 , line of the called station N_3 , v_3 , S', and battery.

The relay S' will open the contact s_7 and thereby interrupt the ringing current. The relay S' furthermore switches the calling line from the impulse relays A₁, B₁ to the contacts s_3 and s_5 , whereby the repeating coil Ue will be inserted into circuit. It will be noted that during the periodical excitation of the relay L the signal "free" will be given to the calling party N_1 over the contacts l_7 and p_4 and an induction coil upon the relay A₁. By the excitation of the relay S' the contact s_1 has been opened and s_2 closed, causing the relay C₂ to be deenergized while maintaining the holding current for the test relay P₂ over the resistance W_1 .

The purpose of this switching operation is the following:—If after completion of the conversation the called subscriber N_3 first restores his receiver the relay S' will be deenergized and thereby the circuit of the ringing relay would again be closed at s_7 . The party N_3 would then believe that a new call had arrived. By opening the contact c_2 at the first excitation of the relay S', however, the contact c_4 will

be opened, so that after deenergizing of the relay S' the ringer circuit will not be closed again. The deenergizing of the relay C_2 will cause the relay S' to perform all 5 functions which had been given to the relay C ; in particular the holding current must be kept close for the test relay T over the contact s_8 . If the called subscriber first restores his receiver the relay S' will be de- 10 energized, contact s_8 will also open, the relay T will be deenergized and open the contact t_1 ; the relay P_2 will drop its armature and close the contact p_5 , whereby a circuit is closed over ground, D , k_4 , p_5 , interrupter 15 un_1 and battery. The brushes o_1 to o_7 will rotate until the brush o_7 when coming to normal releases the relay K , so that the contact k_4 will be opened and the selector S arrested. By the opening of the contact s_8 20 the circuit of the holding current for the relay C_3 in the connector L_1 is interrupted and a contact c_7 closed, thus establishing a circuit over ground, interrupter un_2 , c_7 , brush o_1 , H and battery. This circuit will 25 remain closed until the brush o_{11} gets into its normal position.

After the relay S' has become deenergized the relays A_1 and B_1 are again connected to the trunk line. During the conversation 30 the calling line had been made electrically inoperative by means of a condenser in the repeating coil Ue . These diversities between the switching of the battery over the contacts s_4 and s_6 and the interruption of 35 the contacts s_3 and s_5 can be utilized for controlling supervising relays in the trunk-line office F , as shown in Fig. 1, in such a manner that a signal will be given at the responding of the subscriber N_3 and that 40 another signal will be given after completion of the conversation by the subscriber N_2 . The selectors VW , GW_1 and GW_2 on the side of the calling subscriber are released in the well known manner.

45 If the called subscriber N_3 is busy the testing relay P_4 will not respond and the calling subscriber N_1 will receive busy signal, the circuit being established over a busy machine, contact c_8 in the connector, brush 50 o_{11} , induction coil on the relay A_2 . If the calling subscriber N_1 restores the receiver the circuit for the holding current for the relays P_2 and C_2 will be interrupted in the well known manner. If under these 55 circumstances the relay C_2 falls off it will open its contact c_5 and since s_8 is not closed the relay T will be deenergized and the releasing operations will take place as above described.

60 Having thus described my invention I claim as new and desire to secure by Letters Patent of the United States:—

1. In a telephone exchange system, subscribers' stations, subscribers' lines with un- 65 restricted service, subscribers' lines with re-

stricted service, trunk lines, selectors and connectors to establish connections between said lines, some of said selectors being set by number impulses and by an automatic operation to find a free trunk line, some of said 70 connectors to be used for unrestricted service being set by a plurality of series of number impulses, others of said selectors and connectors for restricted service and in number equal to the number of said series of number 75 impulses being arranged in series and set by a single series of number impulses, the connection with a free trunk line issuing from the last of said selectors being made by a series of relays. 80

2. In a telephone exchange system, subscribers' stations, subscribers' lines with unrestricted service, subscribers' lines with restricted service, trunk lines, selectors and connectors to establish connections between 85 said lines, some of said connectors used for unrestricted service being set by a plurality of series of number impulses, some of said 90 selectors and connectors for restricted service being arranged in series and in number equal to the number of said series of number 95 impulses and each set by a single series of number impulses, the trunk lines connecting said selectors and connectors for restricted service being less numerous than the number of subscribers' lines connected to said connectors for restricted service, said 100 selectors for restricted service having as many sets of wipers as there are trunk lines to be reached by the same number. 100

3. In a telephone exchange system subscribers' stations, subscribers' lines with unrestricted service, subscribers' lines with restricted service, trunk lines, selectors and connectors to establish connections between 105 said lines, some of said connectors used for unrestricted service being set by a plurality of series of number impulses, some of said 110 selectors and connectors for restricted service being arranged in series and in number equal to the number of said series of number impulses and each set by a single series of number impulses, the trunk lines connecting said 115 selectors and connectors for restricted service being less numerous than the number of subscribers' lines connected to said connectors for restricted service, said 120 selectors for restricted service having as many sets of wipers as there are trunk lines to be reached by the same number, and a test relay for each set of wipers. 120

4. In a telephone exchange system, subscribers' stations, subscribers' lines with unrestricted service, subscribers' lines with restricted service, trunk lines, selectors and connectors to establish connections between 125 said lines, some of said connectors used for unrestricted service being set by a plurality of series of number impulses, some of said 130 selectors and connectors for restricted serv-

ice being arranged in series and in number equal to the number of said series of number impulses and each set by a single series of number impulses; the trunk lines connecting said selectors and connectors for restricted service being less numerous than the number of subscribers' lines connected to said connectors for restricted service, said selectors for restricted service having as many sets of wipers as there are trunk lines to be reached by the same number, a test relay for each set of wipers, said relays being arranged in a series, each relay controlling the circuit of the succeeding relay in said series.

5. In a telephone exchange system, subscribers' stations, subscribers' lines with unrestricted service, subscribers' lines with restricted service, trunk lines, selectors and connectors to establish connections between said lines, some of said connectors used for unrestricted service being set by a plurality of series of number impulses, some of said selectors and connectors for restricted service being arranged in series and in number equal to the number of said series of number impulses, and being each set by a single series of number impulses, talking battery and ringing current for said subscribers' lines with unrestricted service being furnished from said connectors for unrestricted service, and talking battery and ringing current for said subscribers' lines with restricted service being furnished from said selectors for restricted service.

6. In a telephone exchange system, subscribers' stations, subscribers' lines with unrestricted service, subscribers' lines with restricted service, trunk lines, selectors and connectors to establish connections between said lines, some of said connectors used for unrestricted service being set by a plurality of series of number impulses, some of said selectors and connectors for restricted service being arranged in series and in number equal to the number of said series of number impulses and being each set by a single series of number impulses, said connectors for unrestricted service and said selectors for restricted service being connected to the said selectors for establishing connections between said lines, the circuits of said selectors for restricted service being arranged as number impulse repeaters to repeat the impulses sent by a calling subscriber to said connectors for restricted service.

7. In a telephone exchange system, subscribers' stations, subscribers' lines with unrestricted service, subscribers' lines with restricted service, trunk lines, selectors and connectors to establish connections between said lines, some of said connectors used for unrestricted service being set by a plurality of series of number impulses, some of said selectors and connectors for restricted service

ice being arranged in series and in number equal to the number of said series of number impulses and being each set by a single series of number impulses, a source of current for operating said connectors and said selectors, talking battery and ringing current for said subscribers' lines with unrestricted service being furnished from said connectors for unrestricted service, talking battery and ringing current for said subscribers' lines with restricted service being furnished from said selectors for restricted service, all connections between the talking lines of said connectors for restricted service and said source of current being broken after setting said connectors upon the desired line.

8. In a telephone exchange system, subscribers' stations, subscribers' lines with unrestricted service, subscribers' lines with restricted service, trunk lines, selectors and connectors to establish connections between said lines, some of said connectors used for unrestricted service being set by a plurality of series of number impulses, some of said selectors and connectors for restricted service being arranged in series and in number equal to the number of said series of number impulses and being each set by a single series of number impulses, a source of current for operating said connectors and said selectors, talking battery and ringing current for said subscribers' lines with unrestricted service being furnished from said connectors for unrestricted service, talking battery and ringing current for said subscribers' lines with restricted service being furnished from said selectors for restricted service, all connections between the talking lines of said connectors for restricted service and said source of current being broken after setting said connectors upon the desired line, another line leading from said selectors to said connectors for restricted service, and circuits connected by said other line for releasing said connectors for restricted service.

9. In a telephone exchange system, subscribers' stations, subscribers' lines with unrestricted service, subscribers' lines with restricted service, trunk lines, selectors and connectors to establish connections between said lines, some of said connectors used for unrestricted service being set by a plurality of series of number impulses, some of said selectors and connectors for restricted service being arranged in series and in number equal to the number of said series of number impulses and being each set by a single series of number impulses, the trunk lines connecting said selectors and connectors for restricted service being less numerous than the number of subscribers' lines connected to said connectors for restricted service, and circuits arranged in said selectors for restricted service for giving a busy signal to

the calling subscriber when all of said trunk lines between said selectors and said connectors for restricted service are occupied.

10. In a telephone exchange system, subscribers' stations, subscribers' lines with unrestricted service, subscribers' lines with restricted service, trunk lines, selectors and connectors to establish connections between said lines, some of said connectors used for 5 unrestricted service being set by a plurality of series of number impulses, some of said selectors and connectors for restricted service being arranged in series and in number equal to the number of said series of number impulses and being each set by a single 10 series of number impulses, the trunk lines connecting said selectors and connectors for restricted service being less numerous than 15

the number of subscribers' lines connected to said connectors for restricted service, 20 and circuits arranged in said selectors for restricted service for giving a busy signal to the calling subscriber when all of said trunk lines between said selectors and said connectors for restricted service are occupied, and circuits in said connectors for restricted service for giving a busy signal to 25 said calling subscriber when the desired subscriber's line is occupied.

In testimony whereof I have signed my name to this specification in the presence of two subscribing witnesses.

HANS STEIDLE.
